United States Patent Office.

IMPROVED DRAG FOR VESSELS.

GEORGE L. UPTON, OF MILBRIDGE, MAINE.

Letters Patent No. 60,287, dated December 4, 1866.

SPECIFICATION.

TO ALL WHOM IT MAY CONCERN:

Be it known that I, GEORGE L. UPTON, of Milbridge, in the county of Washington, and State of Maine, have invented a new and improved mode of preventing ships or vessels, when at sea in storms and gales, from paying off into the trough of the sea, where they roll and labor so hard as to endanger both the vessel and all on board; and I do hereby declare that the following is a full and exact description thereof, reference being had to the accompanying drawings, and to the letters of reference marked thereon.

The nature of my invention consists in an apparatus which when open shows six wings, of any length and width convenient to the size of the vessel for which it is to be used, and when let into the water the drift of the vessel opens these wings, which serve as an anchor to bring the ship or vessel head to the sea and wind, in which position she is not liable to be tripped by the sea.

To enable others skilled in the art to make and use my invention, I will proceed to describe its construction and operation.

I construct my drag, as I term it, as follows, *viz*: First, the shaft A, on the end of which is secured a hub, B, around which, at equal distances, are six hinges, C. The ends of the wings D are secured to the hub B by the hinges C. Upon the shaft A the slide E plays, to which slide, E, the ends of the braces F are secured by being bent into staples in the slide E. The other end of the braces F are secured to the wings by a double-stapled hinge at the point G. These braces serve to hold the wings from spreading any further than needful. At the point G rivets secure the stapled hinge from drawing out of the wings, headed on an iron plate on the outside of the wings. *h* represents a stop upon the shaft A, which prevents the slide E from moving any further up the shaft. *I* represents lines extending from one wing to the other, and secured by a thimble in the end of said lines, *I*, to an oblong staple upon the end of the wings. *J* represents a ring on the end of the shaft A, to which the vessel's hawser can be bent. *K* represents a ring, to which a small trip line is to be bent; so, when the drag is to be taken on board, by slackening the hawser and hauling on the trip line, the drag is reversed and brought to close the wings, and can be easily managed and taken on board again. *L* represents the hawser; *M* represents the trip line; *N* represents a buoy and buoy line; *O* represents the drag closed and as it is when stowed away.

What I claim as my invention, and desire to secure by Letters Patent, is—

The combination of the shaft A, hub B, bevelled wings D, braces F, slide E, constructed substantially as and for the purpose as specified.

GEORGE L. UPTON.
